United States Patent

Des. 238,809

Patented Feb. 10, 1976

238,809

CHAIN FOR A BRACELET OR SIMILAR ARTICLE

Raymond C. Fontaine, Greenville, R.I., assignor to
Textron Inc.

Filed Sept. 27, 1974, Ser. No. 510,077

Term of patent 14 years

Int. Cl. D11—01

U.S. Cl. D45—4 E

FIG. 1

FIG. 2

FIG. 3

FIG. 4

FIG. 1 is a top plan view of a chain for a bracelet or similar article showing my new design;

FIG. 2 is a side elevational view of the chain shown in FIG. 1;

FIG. 3 is an enlarged top plan view of a single top shell of the chain; and

FIG. 4 is an enlarged perspective view of the top shell shown in FIG. 3.

I claim:

The ornamental design for a chain for a bracelet or similar article, substantially as shown and described.
